TOOL FOR APPLYING AND REMOVING WHEEL BALANCE WEIGHTS

Claude W. Mills, Kokomo, Ind.

Application February 17, 1950, Serial No. 7,989

Term of patent 14 years

(Cl. D54—13)

To all whom it may concern:

Be it known that I, Claude W. Mills, a citizen of the United States residing at Kokomo, in the county of Howard and State of Indiana, have invented a new, original, and ornamental Design for Tool for Applying and Removing Wheel Balance Weights, of which the following is a specification, reference being had to the accompanying drawing, forming a part thereof.

Fig. 1 is a front elevational view of a tool for applying and removing wheel balance weights embodying my new design;

Fig. 2 is a side elevational view thereof; and
Fig. 3 is a top plan view thereof.

I claim:

The ornamental design for a tool for applying and removing wheel balance weights, as shown.

CLAUDE W. MILLS.
